UNITED STATES PATENT OFFICE.

THOMAS S. FOX, OF BROOKLYN, NEW YORK.

APPARATUS FOR PRODUCING PRINTING-PLATE DESIGNS.

No. 798,668.

Specification of Letters Patent.

Patented Sept. 5, 1905.

Application filed August 26, 1902. Serial No. 121,063.

To all whom it may concern.

Be it known that I, THOMAS S. FOX, a citizen of the United States, residing in Brooklyn, in the county of Kings and State of New York, have invented certain new and useful Improvements in Apparatus for Producing Printing-Plate Designs, of which the following is a specification.

This invention relates to the manufacture of plates or forms for use in the typographic art, and has for its principal object to provide a simple, efficient, and economical apparatus for producing typographic plates whether the printed design or representation is to be of a simple nature or of a high degree of complexity.

In carrying my improvements into practice I make use of magnetism for giving to the relation existing among the elements of a prearranged design a permanence sufficient for the purpose of photographic reproduction. Such photographic image may be employed in any of the well-known ways to make a printing-surface presenting in detail the various features of the arranged design.

The present apparatus for making typographic printing-plates possesses great flexibility and scope of application in point especially of the practically unlimited number and variety of designs which may be produced. Not only is there inherent in the method involved in the use of the present apparatus for making printing-plates this adaptability to the printing of designs and representations from the simplest to those embodying comparatively great quantity of detail, but one of the most important features relates to the comparatively great facility with which such designs, &c., may be made.

There is illustrated in the drawings attached to the present specification a simple species of apparatus designed to carry into effect my present improvements.

In the drawings, Figure 1 is a plan view of such apparatus, the display-surface thereof supporting certain designs by way of showing the method of using the apparatus. Fig. 2 is a side elevation of the apparatus, the side of the inclosing case or box being removed. Fig. 3 is a section on the plane of the line 3 3 in Fig. 1. Fig. 4 is a perspective view of a portion of the pole-piece of one of the series of magnetically-connected magnets. Fig. 5 is a perspective view illustrating the manner in which a design arbitrarily chosen for illus-

trating is built up, and Fig. 6 is a plan view indicating how a non-magnetic design element may be adapted for coöperation with the present apparatus.

Similar characters of reference designate corresponding parts in all figures.

In the practical application of the present improvements I make use of suitable design elements in the composition of the design or representation desired and employ magnetism for assisting in the convenient production of such composite design or representation and in giving to the relationship thus established among its parts a permanency sufficient to permit the design, &c., to be copied or reproduced. In employing such design elements so arranged—that is, the preestablished design—as the subject of a printing-plate photography will ordinarily be used for the production of a negative. This negative may be converted into or utilized by any suitable or well-known processes for producing a printing-surface.

An apparatus for carrying into practical effect the present method will embody in its most convenient form a display-surface across or over which a magnetic field exists or may be caused to exist, and, while such surface may be substantially a plane surface, obviously it may be otherwise than plane. Moreover, while I may use electromagnets for the production of the magnetic field evidently permanent magnets may be likewise utilized for the purpose.

In the particular apparatus represented in a conventional way in the present drawings a number of electromagnets B are disclosed located within an inclosing case or box. A pole area is thus formed which may have such superficial dimensions as desired or convenient, the magnetic field being derived from a suitable number of magnets. Each magnet is in this instance provided with a core b, all of which cores are in metallic contact with a base-plate 3, of magnetic material, providing thus a path at one end of the magnets for the lines of magnetic force for the purpose of increasing the intensity of the magnets. To the same purpose I prefer to alternate the poles contiguous to which the aforesaid magnetic field is disposed. I have in this particular instance arranged the magnets in a number of lines or series, the poles of all the magnets in each series being connected by a corresponding cross rail or bar 4. This connection is made by means of rods 5, one of

which passes through an opening in the core of a magnet and is attached at one end to the proper cross-bar, while a head 5 at the opposite end takes under the plate 3. Each series of magnets is wound to produce a polarity opposite to that of the series on each side. The leading-in series are designated by 6 and are attached to binding-posts 7 7', mounted upon a fixture 8, of non-conducting material, 10 and from which posts wires 9 9' extend to the solenoids of the magnets. Preferably the aforesaid display-surface is one having comparatively small-dimensioned openings between the areas presented by the free poles of 15 the magnets, and although by no means essential that the configuration and organization should be as illustrated each bar 4 is here provided with a number of flattened pole-pieces 10, metallically connected to the 20 bar. Each pole-piece is located in the space between contiguous pole-pieces on contiguous bars and, moreover, overlaps such pieces. Thus a magnetic field is presented in which oppositely-designated poles alternate with 25 each other. Strips Z, of non-magnetic material, are inserted between adjacent series of pole-pieces. The outer ends of the pole-pieces are all disposed in the same plane and make up the display-surface upon which the 30 design, configuration, figure, representation, &c., is arranged or composed. The elements of such composition or the design elements may of course vary to a great extent and, in fact, be constituted by any article applicable 35 to the purpose. Whatever they are, whether figures, characters, scrolls, pictorial representations, or other articles, they will be capable of being attracted by, and hence attaching themselves to, the display-surface, 40 and hence will necessarily be made of or embody some magnetic material. Thus one obvious expedient is the attachment of pieces of iron or steel to an article of non-magnetic material, as in Fig. 6, in which such pieces 11 45 are secured to the back of the element 12.

While a simple consecutive disposition of parts may alone constitute the design, as indicated at M in Fig. 1, combinations of superposed elements may be made in composing 50 the design. This is indicated graphically in Fig. 5, in which the element 12 is superimposed on the element 13. In this imposed relation it is plain that the outer element may be used for holding down the element 55 beneath it. Moreover, the display-surface may be in whole or in part upon a suitable background, a desired form of which is first placed upon the pole ends of the apparatus, as indicated by 14.

60 The magnetic lines of force being assumed to emanate from the poles, the "design elements" (this term including a background, as aforesaid) may be readily brought into desired relationship, in which they are retained 65 by the magnetism. A photograph copy

may then be made and the image applied in any of the well-known ways to the production of a printing-plate. Subsequently the design by the shutting off of the current or by a sweep of the hand may be removed and 70 the surface prepared for the next composition. By my invention it is evident, therefore, that a practically endless variety of designs, &c., may be made with great facility—designs, in fact, of great complexity and comparable in artistic merit and effect to the 75 productions of the engraver's art.

The employment of magnetism for holding in place the shiftable parts or elements during their adjustment and readjustment in 80 making the final and completed design is especially advantageous in that the position of any one or all of the parts can be changed repeatedly with great facility and without the necessity of tacking or pasting the part fast 85 in each such new position. Thus in all the tentative arrangements leading up to the final design no marking of the parts takes place and the mind of the designer is not distracted or withdrawn from the operation of 90 designing that he has in hand. The display-surface may, moreover, be in any position desired or convenient, from vertical to horizontal, without affecting the firm attachment of the shifted parts, and hence such surface 95 may be so related as to best facilitate the focusing of the camera and the production of the photographic image.

Ordinarily the design constituting the subject from which the photographic image is 100 taken will be of dimensions sufficient to permit of considerable reduction in the image in order that defects, imperfections, &c., may be more or less suppressed if not quite eliminated. 105

Having described my invention, I claim—

1. An apparatus for the production of printing-plate designs photographically transferred from the apparatus to the plate, the same comprising adjustable design elements, 110 means for producing a magnetic field, a supporting-surface located in such field and constituting a display-surface upon which a design is established by a desired arrangement of design elements, and means co-operative 115 with the attractive force of the field for holding the elements on such surface.

2. An apparatus for the production of printing-plate designs photographically transferred from the apparatus to the plate, 120 the same comprising adjustable design elements some at least of which embody magnetic material, means for producing a magnetic field, and a supporting-surface located in such field and constituting a display-surface upon which a design is established by a desired arrangement of design elements. 125

3. An apparatus for the production of printing-plate designs photographically transferred from the apparatus to the plate, 130

the same comprising adjustable design elements some at least of which embody magnetic material, and a series of magnetic pole-pieces whose end faces lie in a common plane 5 and constitute a display-surface upon which a design is established by a desired arrangement of design elements.

4. An apparatus for the production of printing - plate designs photographically transferred from the apparatus to the plate, the same comprising adjustable design elements some at least of which embody magnetic material, and a plurality of series of electromagnetic pole-pieces whose end faces 15 all lie in a common plane and constitute a display-surface upon which a design is established by a desired arrangement of design elements, each series of pole-pieces comprising a plurality of separated pole-pieces 20 which are located opposite the pole-separating spaces of contiguous series.

5. An apparatus for the production of printing - plate designs photographically transferred from the apparatus to the plate, the same comprising adjustable design elements some at least of which embody magnetic material, and a plurality of series of electromagnetic pole-pieces whose end faces 25 all lie in a common plane and constitute a display-surface upon which a design is established by a desired arrangement of design elements, each series of pole-pieces comprising a plurality of separated pole-pieces which are located opposite the pole-separating 30 spaces of contiguous series and extend into such spaces.

6. An apparatus for the production of printing - plate designs photographically transferred from the apparatus to the plate, the same comprising adjustable design elements some at least of which embody magnetic material, and a plurality of series of electromagnetic pole-pieces whose end faces 40 all lie in a common plane and constitute a display-surface upon which a design is established by a desired arrangement of design elements, each series of the pole-pieces being of the opposite polarity to the series contiguous thereto and comprising a plurality of 45 separated pole-pieces which are located opposite the pole-separating spaces of contiguous series and extend into such spaces.

7. A display-surface for the temporary fixation of a design built up of suitable design elements, the same comprising a number of rows of electromagnets.

8. A display-surface for the fixation of a design built up of suitable design elements, the same comprising in combination a number of parallel rows of electromagnets, cross-bars connecting the cores of the electromag-

nets of the respective rows, and flattened pole-pieces secured to the cross-bars with their end faces in a common plane.

9. A display-surface for the fixation of a 65 design built up of suitable design elements, the same comprising in combination a number of parallel rows of electromagnets, cross-bars connecting the cores of the electromagnets of the respective rows, and separated 70 flattened pole-pieces secured to the cross-bars with their end faces in a common plane, the pole-pieces extending from one bar being located opposite the spaces between the pole-pieces extending from contiguous bars. 75

10. A display-surface for the fixation of a design built up of suitable design elements, the same comprising in combination a number of parallel rows of electromagnets, cross-bars connecting the cores of the electromagnets of the respective rows, and separated 80 flattened pole-pieces secured to the cross-bars with their end faces in a common plane, the pole-pieces extending from one bar being located opposite the spaces between the pole-pieces extending from contiguous bars, and the pole-pieces extending from one bar being of the opposite polarity to those extending from contiguous bars. 85

11. A display-surface for the fixation of a 90 design built up of suitable design elements, the same comprising in combination a number of parallel rows of electromagnets, cross-bars connecting the cores of the electromagnets of the respective rows, and separated 95 flattened pole-pieces secured to the cross-bars with the end faces in a common plane, the pole-pieces extending from one bar being located opposite to and projecting into the spaces between the pole-pieces extending 100 from contiguous bars and the pole-pieces extending from one bar being of the opposite polarity to those extending from contiguous bars. 105

12. The combination of a casing, a base-plate, a number of parallel rows of electromagnets whose cores are secured to said base-plate, the coils of said electromagnets being wound to produce opposite polarity of contiguous rows of the magnets, cross-bars connecting the cores of the electromagnets of the respective rows, and flattened pole-pieces secured to said cross-bars with their ends in a common plane, the pole-pieces extending from one bar being located opposite to and projecting into the spaces between the pole-pieces extending from contiguous bars. 110 115
